(Flora, Ind. 46929)

Filed Nov. 30, 1967, Ser. No. 9,598

Term of patent 14 years
(Cl. D23—31)

Fig. 4

FIGURE 1 is a top plan view of an escutcheon for a single lever tub or shower valve embodying my new design.

FIGURE 2 is a side elevation of the same, taken about from the position indicated by the line 2—2 looking in the direction of the arrows.

FIGURE 3 is a further elevational view of the same taken about on the line 3—3 of FIGURE 1, looking in the direction of the arrows.

FIGURE 4 is a bottom view of the same.

I claim:

The ornamental design for an escutcheon for a single lever tub or shower valve, substantially as shown.
